Inventor,
WILLIAM C. BURRELL
By *Jesse Wm. Hinkley*
Atty.

UNITED STATES PATENT OFFICE.

WILLIAM C. BURRELL, OF KANKAKEE, ILLINOIS.

PAVEMENT-MAKING DEVICE.

Application filed December 10, 1923. Serial No. 679,587.

To all whom it may concern:

Be it known that I, WILLIAM C. BURRELL, a citizen of the United States, residing at Kankakee, in the county of Kankakee and 5 State of Illinois, have invented certain new and useful Improvements in Pavement-Making Devices, of which the following is a specification.

This invention relates to pavement making devices.

It will be explained as applied to a parting strip or confining wall used to define and separate contiguous sections of concrete or similar roadway or sidewalk.

15 In building concrete roadways it has become common practice to longitudinally divide the roadway into separated or partly separated sections. Such divisions facilitate the act of laying the concrete and seems to 20 serve, in a large measure, to prevent subsequent irregular cracking. It may also facilitate repair and replacement of portions of the pavement. In carrying such work into practical execution it is essentially necessary 25 that the aforesaid strip of metal shall be firmly and securely supported and held on one edge and that the holding means shall engage the strip in such manner as to prevent any relative movement of the connected 30 parts.

One of the objects is to provide an improved device of the character described.

Another object is to provide an improved, contractible strip-supporting pin for securely holding and supporting the strip edge on during the operation of laying the concrete in place.

Another object is to provide a strip which in cooperation with the pin will effect interlocking of the strip sections.

40 A further object is to provide an improved supporting and holding pin which will facilitate the application of the strips and which is self-adjusting to hold the strips together and support them in place.

Another object is to provide an improved strip-supporting pin which is self-adjusting with respect to the orifice into which it may be driven; which possesses maximum 50 strength proportional to its weight; which may easily and cheaply be constructed and applied.

Another object is to provide an improved key or pin to support the strip.

55 Other objects and advantages will herein-after appear from a consideration of the fol-

lowing description, when taken in conjunction with the drawings, wherein:

Fig. 1 is a perspective view of two interlapped strips as they appear when supported on the ground for the purpose described. 60

Fig. 2 is an enlarged cross-section taken on line 2—2 of Fig. 1.

Fig. 3 is a section taken on line 3—3 of Fig. 2. 65

Fig. 4 is a modification of Fig. 1.

In all the views the same reference characters are employed to indicate similar parts.

The strip 5 may be made of suitable metal, such as so-called galvanized sheet iron. The 70 strip has a longitudinally extending laterally projecting rib or bead 6, thru which a pin or key 7 is to be driven into the ground.

In the several figures of the drawings I have shown the pin driven thru corresponding registering holes 8 in the beads near the ends of adjoining strips. In this event the pin 7 not only supports both strips in edge on position, but also holds the lapped ends together. There may be one or more holes 8' intermediate the ends of the strips thru which to insert the supporting pin 7 for additional strength. 75

To make a continuous strip of a plurality of sections, the ends are lapped, as shown in Fig. 1 and the pin is placed thru the registering holes. In Fig. 4 the ends of adjoining strips are abutting to bring the strips in true alignment, and a clip 9 having like registering holes is caused to bridge the joint and the pin is then driven thru all of the holes. 80 A single clip 9 may be used, in which event two pins may be employed.

Another pin may be driven thru the holes shown by dotted lines at 10. Instead of using two pins the clip 9 may be riveted to the strips 5 or 5', as at 11. If a more secure joint is desired another clip 9' may be placed on the opposite sides of the strips and riveted as described or held by use of two pins. 95

The pin 7 is tapered near its point in two directions so that it will easily pass thru the holes 8. The pin is larger in its mid-portion than the holes after the tapered point is passed so that it will be transversely contracted, and self-adjusting, as it is driven and thus make a tight substantially unyielding fit with the holes. 100

The wall of the pin is uniform in transverse thickness. It is preferably punched of 110 sheet metal and formed into parti-cylindrical configuration having a longer radius

than the radii of the holes thru which it is to be driven.

The pin is shown to extend circumferentially to an extent equal to less than one-half of a circle. It may extend further, if desired. It is light, strong, inexpensive, self-adjusting to tightly fit the holes, and may easily be driven into the ground, or into an opening in more unyielding material 10 in which it will secure itself because of its transversely contractible nature.

The projection 6 may consist of a crimp in the metal to form a bead. The projection stiffens the strip and also forms a 15 groove or tongue, as desired, in the cement block. The adjacent block forms the other member of the tongue and groove joint.

The lower end of the pin is tapered in two directions so as to more easily pass thru the 20 holes in the strip into which it is to be driven. The tapering effect is accomplished by having the salient edges converge toward each other near the pointed end.

The largest diameter of the pin is from 25 the outside surfaces of its longitudinal terminal or salient edges so that when the pin is driven into a hole of smaller diameter it will contract transversely by these edges approaching nearer together and as the pin 30 is made of resilient metal it will tightly engage all of the holes or apertures into which it may be driven.

Having described my invention what I claim as new and desire to secure by Letters Patent, is:—

1. In combination with a strip having a laterally projecting, longitudinally extending bead, said bead having perforations extending transversely of the wall to receive 40 a pin to be driven therethrough to hold the strip on its edge and a laterally contractible pin larger in diameter than said perforations to be driven thru said perforations.

45 2. In combination with a strip of sheet metal, crimped outwardly near its median transverse dimensions to form a laterally projecting longitudinally extending bead, said bead perforated in a line substantially 50 parallel with the margins of the strip to

receive a pin to support the strip on one side edge, and a laterally contractible pin larger in its larger diameter to be driven thru said perforations and into the ground.

55 3. In combination with a strip of sheet metal crimped outwardly to form a laterally projecting longitudinally extending bead, said bead perforated, near its juncture, with the margins of the strip, and a transversely contractible pin larger in diameter than 60 said perforations to pass thru the perforations to support the strip on one of its edges.

65 4. In combination with a strip of sheet metal crimped outwardly to form a laterally projecting longitudinally extending bead, said bead perforated near its juncture with the margins of the strip; another strip having similar perforations when in lapped relation with the first mentioned strip and in register therewith, and a transversely 70 contractible pin originally larger in one diameter than said perforations thru which it is to be driven to hold the strips together.

75 5. A pin, for the purpose described, comprising a trough-like strip of resilient sheet metal curved transversely into parti-circular form and uniformly tapered throughout the major portion of its length and tapered in two directions near its point.

80 6. A support for pavement parting strips comprising a pin of parti-circular cross section formed from a sheet of metal curved uniformly throughout the major portion of its length and having adjacent edges of the sheet near one end converge toward a point. 85

85 7. A support for pavement parting strips comprising a hollow pin of parti-circular cross-section throughout the major portion of its length formed of resilient sheet metal and having the longitudinal edges of the pin near one end converge toward a point. 90

90 8. A transversely contractible pin made of sheet metal and curved transversely and uniformly throughout the major portion of its length and uniformly tapered longitudinally near one end.

In testimony whereof I hereunto set my hand.

WILLIAM C. BURRELL.
